UNITED STATES PATENT OFFICE.

JOSEPH N. EARLY, OF NEW YORK, N. Y.

STREET-SIGN.

1,157,515.

Specification of Letters Patent.

Patented Oct. 19, 1915.

Application filed June 17, 1914. Serial No. 845,605.

To all whom it may concern:

Be it known that I, JOSEPH N. EARLY, a citizen of the United States, and a resident of the city of New York, Riverdale, borough 5 of the Bronx, in the county of Bronx and State of New York, have invented a new and Improved Street-Sign, of which the following is a full, clear, and exact description.

My invention has special reference to improvements in signs and more particularly to street signs carried by posts or the like.

The essential object of the invention is comprehended by the provision of an improved street sign and more particularly 15 attaching and adjusting means for a sign or signs whereby the latter may be securely and accurately adjusted to extend in the same direction as the street or streets which they are intended to designate or to be so 20 accurately adjusted as to harmonize with the direction of the street, avenue or place to correctly indicate to an observer the course and location of such street, avenue or place.

25 The invention further comprehends the provision of an improved sign device including a novel sign and adjusting means particularly adaptable to a post and which is clamped to the latter in a novel way whereby 30 movement of the sign or signs after once being adjusted, as well as displacement of the sign plates constituting a portion thereof, is obviated.

With the above and other objects in view, 35 the invention resides in the peculiar combination and arrangement of parts to be hereinafter more fully described, illustrated and claimed, it being also an object to provide a device which is simple in construction, durable and efficient.

40 Reference is to be had to the accompanying drawings forming a part of this specification, in which similar characters of reference indicate corresponding parts in all the 45 views, and in which—

Figure 1 is a perspective view of a street sign carrying two crossed signs in harmony with the angle of intersection of a street and an avenue, a portion of the post supporting the same being shown; Fig. 2 is an enlarged vertical sectional view partly in section of the upper end of a post and sign carrying parts supported thereon, the sign plate being omitted from the lower frame; 50 Fig. 3 is an enlarged cross sectional view taken on the line 3—3 of Fig. 2; Fig. 4 is a

sectional view taken on the line 4—4 of Fig. 2; Fig. 5 is a perspective view similar to Fig. 1 but showing a single sign instead of crossed signs; Fig. 6 is an inside elevation of one of the sections or frames of a sign; Fig. 7 is a plan view thereof engaged with the reduced portion or attaching standard of the post, the latter being shown in section; Fig. 8 is a face view of one of the frames; Fig. 9 is a sectional view taken on the line 9—9 of Fig. 6; Fig. 10 is a sectional view taken on the line 10—10 of Fig. 6; Fig. 11 is a sectional view taken on the line 11—11 of Fig. 6; and Fig. 12 is a sectional view taken on the line 12—12 of Fig. 6.

As illustrated in the drawings, the improved sign is adapted to be supported upon a post 13 preferably of hollow metal, to which the reduced portion of attaching 75 standard 14 of the sign is secured. For this purpose the attaching standard, which is preferably cast solid, has or is formed with an enlarged socket 15 at its lower end and this socket is cut away on one side as 80 shown at 16 so that the remaining side 17 extends over slightly more than 180°. Since the cut-away portion extends more than half the distance of the inside depth of the socket, the latter may be readily applied to 85 the upper end of the post to receive the post and be held against displacement until the application of a removable side portion or clamping jaw 18 which fits into the cut-away space in opposition to the side 17 forming 90 the other clamping jaw. The jaw 18 extends over less than 180° and co-operates with the jaw 17 so that it may form a circle of smaller diameter than the normal interior diameter of the socket proper. The jaws are 95 provided with co-acting apertured ears 19 through which clamping members or bolts 20 are passed to draw the jaws in contact with the exterior face of the post and securely fasten the standard thereto.

100 The standard is provided with an enlarged head 21 providing a bottom shoulder 22 for a purpose to be hereinafter explained, and as shown in the drawings the design of this head may be changed to agree with the 105 styles of post or the desires of the buyer. The standard is further provided at spaced points vertically of its height with longitudinal corrugations 23 extending around the standard and providing extensions and 110 intermediate depressions which are preferably convexly and concavely arcuate, as is

more clearly shown in Fig. 3 of the drawings. These corrugations are formed within the area of the surrounding face of the standard so as to provide, if desired, 5 shoulder portions 24 at the ends of the corrugations and said corrugated portions are preferably located near the upper and lower ends of the standard adjacent to the shoulder produced by the enlargement 21 10 and the supporting part or shoulder produced by the socket 15, and also centrally of the height of the standard, as is more clearly shown in Fig. 2 of the drawings. This arrangement is more particularly adapted for 15 use in connection with a criss-cross four-way sign post, as illustrated in Fig. 1 of the drawings, wherein two signs placed one above the other and carried by the standard are held in crossed relation to harmonize or 20 extend in the direction in which the streets extend. As the number of corrugations is always more than four, the angular distance between the consecutive corrugations is always less than 90°, consequently the 25 larger the diameter of the standard and the smaller the corrugations, the less the angular distance between the same.

The signs each comprise a pair of frames 25 which are of rectangular contour and 30 which are made up of malleable iron or other spring metal or material capable of withstanding considerable strain and returning to its normal position when bent or strained as the case may be. These frames 35 are curved throughout their longitudinal extent, the top and bottom portions 26 thereof bulging outward at the center and curving inward at their ends, while the end portions 27 of the frames are bulged outwardly 40 at the center, as shown in Fig. 9 of the drawings, for a purpose to be hereinafter more particularly specified. The top and bottom portions as well as the ends are preferably shaped in the form of moldings on their exterior faces, as shown at 28, and intermediate 45 the lengths of said top and bottom portions the frames are thickened to prevent material flexing at these points, and provided with inward extensions 29 producing interior rabbets or shoulders 30, while said 50 extensions are also formed with a plurality of corrugations 31 providing extensions and intermediate depressions extending transversely of said top and bottom portions and 55 located on an arc concentric to the center of the standard and conforming to the contour of the corrugations of the standard to coact and fit to the extensions and depressions thereof, as is more clearly shown in 60 Fig. 7 of the drawings. At either side of the corrugations the top and bottom portions are provided with apertures 32 while the exterior faces of the sides are provided with square recesses 33 and the ends of each 65 frame are provided with inward extensions

34 extending partly into the sides to provide end rabbets or shoulders which together with the rabbets produced by the extensions of the top and bottom portions serve to receive and retain sign plates 35 against displacement vertically and longitudinally. 70

The ends of the frames are provided with apertured ears 36 and these ends are normally bent so that when two of the frames are brought together against the attaching 75 standard with the corrugated faces co-engaged and with the sign plates in position, the top and bottom portions of said ends will contact and by passing bolts 37 through the apertured ears 36 and clamping 80 the frames together to tightly hold the sign plates and the frames in position and prevent the ends from separating at the corners as would occur if these end portions were made straight or bowed inwardly instead of outwardly. Clamping bolts 38 are also engaged through the apertures 32 accommodated in the recesses 33 at their ends and in this manner the co-engaging corrugated faces will be positively interlocked 85 by reason of the frames being drawn into tight engagement with the corrugated portions of the attaching standard so that when a sign is set at any particular adjustment on the standard it will be retained against 90 movement. 95

As shown in Fig. 1, two signs are provided which cross each other and are disposed one above the other as shown in Fig. 2, the corrugations of the lower frames 100 engaging the lower corrugations of the attaching standard and the lower part of the intermediate corrugations, while the upper frames engage the upper part of the intermediate corrugations and the upper corrugations, the corrugations being made of sufficient length or height to accommodate the corrugated portions of the frames even in view of slight variations in the widths of the corrugated portions and frames. In 105 Fig. 5 a single sign 39 is shown the frame 40 of which occupies the full height of the attaching standard and is similarly secured thereto except that the ends of the frames are provided each with a pair of apertured 110 ears 41 through which clamping bolts 42 are engaged, but otherwise the structure is 115 the same.

By the construction described an adjustment in the angular positions of the signs 120 relative to the post and attaching standard thereof is permitted. By varying the diameter of the attaching standard and the number of corrugations on the lateral surface thereof, the angular distance 125 between the corrugations is varied and, therefore, a better adjustment of the sign or signs on the standard is obtained. It is also to be understood that the structure while specifically described in connection 130

with a street sign, is adapted for general application for road signs or other signs and that any number of crossing signs may be employed where two or more streets intersect or where it is desirable to dispose a plurality of signs at varying angles relative to each other.

Having thus described my invention, what I claim as new and desire to secure by Letters Patent is:—

1. A street sign, comprising a standard having shoulders near its ends and longitudinally extending corrugations and intermediate depressions at spaced points around its circumference, spring metal frames having top and bottom extensions coöperating with said corrugations and depressions to dispose the frames at different angular adjustments relative to the standard, sign plates held in the frames, and clamping means engaged through the frames near their ends and central portions to clamp the same together and secure opposed binding contact of the frames with the standard.
2. The combination with a post and a standard carried thereby, said standard being of reduced diameter relative to the post and having surrounding convex corrugations at spaced points vertically of its height; of signs adjustably carried by said standard, said signs each comprising a pair of frames bulged outward at the centers of their top and bottom portions and tending to bulge outward at their ends, extensions upon the inner faces of the frames providing rabbets, sign plates seated in said rabbets, said frames having their top and bottom extensions provided with corrugations on curved lines conforming to the curvature of the standard, clamping means connecting the frames at either side of the standard, and clamping means connecting the frames at their ends and coöperating with said first named connecting means to draw the frames together and in binding contact with the standard, the release of said clamping means permitting independent angular adjustment of the signs relative to each other and the standard.
3. A street sign comprising a post having an upper end portion of reduced diameter with shoulders at the upper and lower ends thereof, said upper portion having a series of surrounding corrugations and intermediate depressions at spaced points vertically thereof adjacent to said shoulders, spring metal frames of bowed formation having sign seats at the inner sides thereof and horizontally disposed inwardly projecting notched portions coöperating with the depressions aforesaid and means to clamp the frames on opposite sides of the post in opposed relation and in contact at the ends of

the frames, said means holding said projections in engagement with the depressions, whereby turning of the frames and plates on the post is normally prevented, said means being adapted to be operated to permit adjustment of the plates on the post.

4. A street sign comprising a sign bearing part having spaced series of vertically alined circumferential convexed corrugations and intermediate concaved depressions of similar but reverse curvatures, frames having top and bottom portions with extensions projecting inwardly at their intermediate portions, said extensions having their inner edges provided with alternate corrugations and depressions arranged in a concaved line to conform to the curvature of the corrugations of the attaching part, sign plates carried by said frames between said extensions and limited against vertical displacement thereby, said frames being formed at their ends to prevent displacement of the signs horizontally and having bulged end portions and means to clamp said frames together to secure the same against movement on the attaching part said clamping means being adapted to be loosened to permit angular adjustment of said frames.

5. In a street sign, the combination with a post and a sign bearing standard; of a sign adjustably carried by the standard, a socket at the lower end of the standard to receive the upper end of the post and forming a shoulder to support the sign, said socket having a cutaway portion, a jaw fitted in said cutaway portion and means connecting the jaw and socket to clamp the jaw against the post to rigidly secure the attaching standard thereto.

6. A street sign or the like, comprising a tubular post and a cast metal sign attaching standard of reduced diameter relative thereto, said standard having an enlarged socket formed at its lower end to fit over the upper end of the post, said socket having a cutaway portion, a jaw to fit said cutaway portion, both said jaw and said socket having apertured projections, fastening means connecting the jaw and socket through the medium of said projections to clamp the jaw and socket member against the post to rigidly secure the standard thereto and a sign adjustable on the standard, said standard being adapted for adjustment with respect to the post.

In testimony whereof I have signed my name to this specification in the presence of two subscribing witness.
